UNITED STATES PATENT OFFICE

1,994,300

ILLUMINATING DEVICE

Cornelis Bol, Eindhoven, Netherlands, assignor
to General Electric Company, a corporation of
New York

Application September 8, 1933, Serial No. 688,663
In Germany September 27, 1932

1 Claim. (Cl. 240—11.4)

The present invention relates to illuminating devices generally and more particularly the invention relates to such devices in which a gaseous electric discharge lamp requiring a transformer is the light source.

The object of the invention is to provide a compact, easily assembled lamp unit comprising a gaseous electric discharge lamp device and a transformer for said device and a lamp unit of such construction that the parts thereof are separately and easily removable therefrom. A further object of the invention is to provide such a lamp unit which is easily incorporated in reflectors now used for incandescent lamps. Still further objects and advantages attaching to the device and to its use and operation will be apparent to those skilled in the art from the following particular description.

In accordance with these objects the new and novel lamp unit comprises a support for the gaseous electric discharge lamp device and for the transformer of said lamp. Said support likewise accommodates a heat conservator for said lamp which is necessary for some types of discharge lamp devices, particularly those having a gaseous atmosphere comprising a difficulty vaporizable material, such as sodium. The lamp and the heat conservator therefor are separately and easily removed from said support. The support and the transformer are enclosed by a housing which is removable from the lamp unit without disturbing the lamp device or the heat conservator and the lamp device and the heat conservator project from the housing. Said housing is provided with ventilating means and baffles so that the elements, or parts of the elements, of the lamp unit enclosed therein do not attain a harmful temperature during the operation of the lamp device.

The invention will be readily understood by an inspection of the drawing accompanying and forming part of this specification and a perusal of the following detailed description thereof.

Fig. 1 of the drawing is a front elevational, partly sectional view of the new and novel lamp unit.

Fig. 2 is a sectional view along the line 2—2 of Fig. 1, and

Fig. 3 a side elevational view of the new and novel lamp unit mounted on a support and in a reflector said reflector being shown in section.

Like numbers denote like parts in all the figures.

Referring to Figs. 1 and 2 the new and novel

lamp unit comprises a transformer 17 mounted on two support-strips 2. Said support-strips 2 are attached to the part 1 which is the top of the housing and which has an opening 19 therein to accommodate the current cable 20 which is connected to the transformer 17 and to accommodate support means for the lamp unit. A plate 3 of insulation material, such as hard-rubber or asbestos, provided with plug-contacts 4, is attached to said support strips 2. Said plug-contacts 4 are electrically connected to the transformer 17 by suitable current leads. The contacts 4 accommodate the prongs of the base 8 of the gaseous electric discharge lamp device 9. Said lamp 9 comprises a cathode which is electron emitting when heated and two anodes (not shown for purposes of simplicity) and has a gaseous atmosphere therein comprising a rare gas and a metal vapor, such as neon and sodium vapor, and is similar in structure to the lamp device disclosed in my German Application Number 34,220, filed in Germany September 26, 1932 which corresponds to my United States Patent Number 1,951,124, March 13, 1934. It is desirable in this type of lamp device that the radiation of heat from the container of said lamp device be reduced to a minimum to maintain an effective vapor pressure therein during the operation thereof and a heat conservator is provided for this purpose. The heat conservator illustrated in the drawing is a double-walled jacket 6 and the space between the walls of said jacket is evacuated, when desired, but it will be understood of course, that I contemplate the use of other types of heat conservators in the lamp unit. Said jacket 6 is provided with a bayonet base 21 which slips over and is supported by the plate 5. Said plate 5 consists of heat insulating material, such as hard-rubber or asbestos, and is supported by rods 7 attached to said supports 2. The heat insulating plate 5 reduces the transfer of heat from the lamp 9 to the transformer 17 to a minimum and the plate 3 serves as a baffle for this purpose. The base 8 passes through and extends beyond the plate 5 and the space between said lamp 9 and the conservator 6 is closed by a ring 10 comprising a circular, coiled metal spring embedded in heat insulation material, such as asbestos. Said ring 10 also serves to protect the transformer 17 from the heat of said lamp 9. The stem of the container of the lamp 9 is located in the elongated base 8 and out of the space enclosed by said ring 10 and said jacket 6 so that said stem part is cooler than the other

parts of the container of the lamp 9 which avoids cracking at said stem part. When desired the base 8 is provided with ventilating means, such as openings 20, for this purpose all as disclosed in my patent referred to here-
5 tofore.

The housing 11 for said transformer 17 is attached to said cover 1 by means of screws 12 and is easily removable therefrom. An annular slot is present between the overlapping parts 10 of said housing 11 and said cover 1 for ventilating the interior of said housing 11. The lower end of said housing 11 is skirted and is partly closed by a cap 13. Said cap 13 is supported by 15 triangular rods 14 inserted in a clamp comprising the part 16 and the set screw 15 as shown in Fig. 2 of the drawing. Said cap 13 is separated from the outer wall of the jacket 6 to avoid the direct transference of heat from said 20 jacket 6 to said cap 13 and to provide ventilation for the parts enclosed in said housing 11. When the cap 13 is made of heat insulating material, such as hard rubber, this separation may be present, or not, as desired.
25 The above described lamp unit is compact, easily assembled and the parts thereof, such as the jacket 6, the lamp 9, the cap 13 and the housing 11 are separately and easily inserted into and removed from said lamp unit which is 30 of great advantage in inspecting, cleaning or repairing the transformer 17, the lamp 9 and the jacket 6, particularly where the lamp unit is located in difficultly accessible places, such as high poles. The housing 11 is removable from 35 the lamp unit without removing the lamp 9 or

the jacket 6. The transformer 17, which furnishes the heating current for the thermionic cathode of said lamp 9 or the operating current for said lamp 9 or both, as desired, is protected from the weather and dirt by said housing 11. The lamp unit is easily mounted on a support rod 25 and in a parabolic reflector 18 (Fig. 3) which is advantageous in street lighting, beacon work or the like. The lamp unit is mounted on support 25 by inserting holding means in the 10 opening 19.

What I claim as new and desire to secure by Letters Patent of the United States is:—

A lamp unit comprising in combination, a gaseous electric discharge lamp device having a 15 stem located in a perforated base, a heat conservator therefor, a resilient ring of heat insulating material interposed between and pressing against said conservator and the container of said lamp device, a transformer for said device, 20 and a housing-support having ventilating means at each end thereof, said transformer being mounted in said housing-support, said lamp and said conservator being mounted out of said housing-support, said lamp being mounted in said 25 heat conservator, the space between said lamp and said heat conservator being divided from the interior of said housing-support by said heat insulating ring, the housing part of said housing-support, said lamp and said heat conservator being separately removable from said lamp unit, said base being located in said ventilated housing-support and said ring being adjacent the joint between said base and said device.

CORNELIS BOL. 35
